George Beard, Junr. of West Whiteland Township, county of Chester & State of Pennsylvania -

Letters Patent.

The schedule referred to in these Letters Patent, forming part of the same, containing a description in the words of the said George Beard Junr. himself, of his improvement in the plan for marking off & cutting out garments, called "Beard's graduated Pattern rule."

To all to whom these Presents shall come

Be it known, that I George Beard, Junr. of West Whiteland Township in the county of Chester and state of Pennsylvania, have invented a new and useful rule or plan for marking off & cutting out, coats, vests, pantaloons, & all other garments or parts of clothing called Beard's graduated pattern rule. & that the following is an exact description of the construction & operation of said rule as invented by me - if a small sized garment is marked off complete on paper near the centre, a large size is also marked off near the extremity and all the intervening sizes graduated, numbered & marked on the space between. The sizes are marked at every point and curve over the pattern with numerical figures, each size being marked with its corresponding number. At each numeral mark an orifice or incisure is perforated thro' the pattern so that it can be laid on a piece of cloth or other stuff & a garment of any size marked off complete by marking thro' the incisions.

The component parts of a garment may be put separately on separate pieces of paper, when more convenient.

A scale of variations for the different sizes is also marked on the pattern, accompanied with written directions for applying them, when the garment is intended to fit a person who is misshapen -

The plan of graduating sizes on a pattern, as well as the adaptation of such patterns, to marking off & cutting out coats, vests, pantaloons and all other garments or parts of clothing
